UNITED STATES PATENT OFFICE

124,508

DESIGN FOR A DRESS OR SIMILAR ARTICLE

Anna Naubert, Chicago, Ill.

Application September 26, 1940, Serial No. 95,400

Term of patent 3½ years

To all whom it may concern:

Be it known that I, Anna Naubert, a citizen of the United States, residing at 7728 N. Marshfield Ave., Chicago, in the county of Cook and State of Illinois, have invented a new, original, and ornamental Design for a Dress or Similar Article, of which the following is a specification, reference being had to the accompanying drawing, forming part thereof.

The trimming on the pocket members is comprised of sequins.

I claim:

The ornamental design for a dress or similar article, substantially as shown and described.

ANNA NAUBERT.
